UNITED STATES PATENT OFFICE

GEORGE HENRY WHEARY, OF RACINE, WISCONSIN, ASSIGNOR TO WHEARY TRUNK COMPANY, OF RACINE, WISCONSIN, A CORPORATION OF WISCONSIN

BAGGAGE CARRIER

Application filed June 7, 1926. Serial No. 114,169.

There is a demand for a wardrobe baggage carrier capable of being carried as a suit case and this invention has as an object the provision of an improved wardrobe type suit case which is of sturdy but neat construction and which has wardrobe means and a removable receptacle for carrying shirts, handkerchiefs and other articles, which may be entirely eliminated if necessary to make the case a full wardrobe type.

Another object of this invention resides in the provision of an improved baggage carrier of the character described having a well or space at the bottom in which the lower ends of the garments hang to thus prevent their accidental contact with the floor while being removed or replaced to thus prevent soiling.

A further object of this invention resides in the provision of an improved wardrobe type suit case having a removable receptacle or container, the lower end of which extends into a well or compartment formed in the bottom of the main section of the case.

It is a further object of this invention to provide an improved baggage carrier having one or more containers readily removably mounted in the stationary section thereof.

And a still further object of this invention resides in the provision of an improved baggage carrier of the character described in which an extension member on the lower end of the main section forms a continuation of the closure, a band or guard extending around the marginal edge portions of the main section providing means for entirely encasing garments hung therein in the event the case is being used entirely for wardrobe.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated several complete examples of the

physical embodiment of my invention constructed according to the best modes I have so far devised for the practical application of the principles thereof, and in which:

Figure 1 is a perspective view of a wardrobe suit case embodying my invention, the case being in full open position and the removable compartment or container being removed therefrom and in open position, parts being broken away;

Figure 2 is a fragmentary perspective view similar to Figure 1 of a slightly modified form of my invention;

Figure 3 is a fragmentary, sectional view taken through Figure 1 on the plane of the line 3—3, and showing the removable compartment positioned within the case;

Figure 4 is a view, partly in section and partly in elevation, taken transversely through a further modified form of baggage carrier;

Figure 5 is a fragmentary, perspective view of one of the sidebars and illustrating the means for detachably securing the removable container in position;

Figure 6 is an enlarged, fragmentary view, partly in section and partly in elevation, of the upper end portion of a baggage carrier illustrating an additional type of means for preventing the shifting of the container, and

Figure 7 is a view similar to Figure 4 of still another modified form of my invention in which two removable containers are employed.

Referring now more particularly to the accompanying drawings, in which like numerals designate like parts throughout the several views, 5 designates the main section of a baggage carrier of the wardrobe type suit case having its open front normally covered by a closure 6 hingedly connected therewith for movement in a vertical plane. The bottom 7 of the closure is positioned on a higher plane than the bottom 8 of the section 5 and the space beneath the bottom of the closure is filled when the carrier is closed, by an extension member 9 projecting from the bottom of the main section and forming therewith a rigid, one-piece bottom for the baggage carrier.

The extension member has side walls 10, forming substantially continuations of the lower portion of the side walls 11 of the main section, connected at their forward ends by a front wall 12, the bottom of the extension member being a continuation of the bottom 8 of the section. The closure 6 has its side walls 13 of a depth equal to the distance the member 9 extends from the main section so that when closed the baggage carrier presents an unbroken appearance. If desired, valance means 14 extend from the marginal edges of the closure walls 13 to overlie the adjacent marginal edges of the section 5.

An upstanding band or flange 15 is secured to the upper marginal edge portions of the extension member walls to provide an abutment against which the bottom portions of the closure engage when closed thereover. Suitable fastenings or locking means 16 are carried by the closure and section to lock the carrier closed and a handle 17 is carried by one side wall 11 of the section 5 to permit the handling of the carrier as a suit case.

In Figures 1, 4 and 7, I have illustrated a baggage carrier of the type particularly adapted for use in connection with men's garments wherein as shown in Figure 1, a single wardrobe trolley 18 is suitably mounted from the top wall 19 of the section 5 to support garment hangers 20, the trolley preferably extending beyond the top and side walls of the section a distance substantially equal to the depth of the closure to lie close to its front wall 21 when closed. A movable extension 22 is carried by the trolley 18 to permit the movement of the hangers outwardly of the section for convenience in removing. A band or guard 23 is secured to the inner faces of the section walls 11 and 19 and projects therebeyond to telescope within the closure 6 when closed, the guard providing a complete encasement for garments hung within the section when the carrier is employed as a full wardrobe suit case.

Provision is made for carrying articles, other than garments capable of being hung from a hanger, in the form of a box or receptacle 24 comprising two hingedly connected sections or parts 25 of a width to fit between the sides of the guard 23 and of a height to substantially fill the space between the bottom of the extension and the hangers 18. Vertical angle irons 26 are mounted at the inner marginal edges of the guard 23 to provide abutments against which the rear of the receptacle 24 engages when secured in the main section.

If desired, the receptacle 24 may be removably secured in place by latch members 27 engaging in locking recesses 28 in the upper portion of the angle irons 26 and pivot members 29 engaging recesses 30 in the lower portions of the angle irons. In use it has been found practical to set the receptacle 24 with-

in the well or compartment formed by the extension, although the members 27 and 29 provide means for preventing movement of the receptacle within the carrier.

The carrier 24 is provided with a handle 31 for convenience in removing the same from the baggage carrier or for carrying it from place to place and lock means 32 are provided for securing the sections 25 closed.

That type of baggage carrier illustrated in Figure 2 is especially designed for ladies' garments and the top of the section 5 is closed by a hinged cover 33 having its inner surface cushioned, as at 34, to cooperate with hangers 35 mounted on a double trolley 36 to hold the hangers and garments thereon in place, as will be readily apparent. In this form of my invention the receptacle 24 may be entirely eliminated or may be set within the well formed by the extension member 12.

In Figures 4 and 5, a slightly modified means for securing the receptacle 24 in position is illustrated wherein the lower end of each angle iron 26 has an extension 37 which is curved forwardly and then directed upwardly to form a recess 38 in which a trunnion or stud 39 projecting laterally from the bottom portion of the adjacent side of the receptacle 24 is engageable. The upper end of the front portion of each angle iron 26 is formed with an extension 40 which is folded downwardly along the rear of the angle iron, as at 41, and then curved rearwardly and directed upwardly to provide a recess 42, in which a trunnion or stud 43 projecting from the adjacent side of the receptacle upper end is engageable. The recess 38 is deeper than the recess 42 to facilitate mounting of the receptacle in place, as the studs 39 may be engaged with the angle irons and thus guided into the lower recesses behind the extensions 37 before the uppermost studs or trunnions 39 enter the recess 42. The extensions 40 projecting above the recesses 42, serve to guide the studs 43 into their recesses. The receptacle when in place, is supported from the trunnions 39 and 43.

Cooperating with the trunnions 39 and 43 is a cleat or stop 44 fixed to the inner side of the front wall of the door 6, the cleat being engageable over the upper or top portion of the container to prevent its shifting or accidental disengagement from its supports while being handled. In Figure 4, the cleat 44 is illustrated as a spring adapted to be under tension when engaged with the receptacle and in Figure 6 the same is illustrated as a rigid type.

The application of my invention to a steamer trunk having a hinged cushion top is illustrated in Figure 7, in which two containers 45 and 46 are preferably mounted. The top container 45 is similar in construction to the one illustrated in Figure 4 with the exception as to its overall height and the lower

5 container 46 is likewise similar with the exception that its depth is greater than that of the upper one and its lower end is held in place by engagement in the well formed by the extension member and, if desired, by a cleat or stop 47 fixed to the bottom 8 to prevent the inward movement of the receptacle. As the depth required at the bottom portion of a wardrobe section is considerably less than that necessary at the upper portion, the depth of the lower container may be increased 10 as described above to permit its use as a hat box or the like.

15 The trolley structure is preferably extended beyond the main section to a point juxtaposed the outer wall of the closure when closed so that the containers may be removed and the carrier utilized for all garments. In many instances, the upper container 45 only 20 need be removed to utilize the carrier as an all-garment one. It will be readily apparent that various modifications may be made in the construction shown and as the description with respect to the modifications hereinbefore described applies to the construction shown in Figure 7, further description is deemed unnecessary.

25 From the foregoing description taken in connection with the accompanying drawings, it will be readily apparent to those skilled in the art to which an invention of this character appertains that I provide an improved and novel baggage carrier in which the clothes are protected against dragging onto the floor while the hangers 20 and 35 are being shifted, and one capable of use either as an all or part garment carrier.

30 What I claim as my invention is:

1. A wardrobe type suit case, comprising a 35 main section, a closure for the section, means hingedly connecting the section and closure the bottom of the closure being on a higher plane than the bottom of the section, an extension on the bottom of the section and forming therewith a one piece bottom for the case, said extension filling the space beneath the closure bottom, a guard extending about the marginal edges of the section to provide an encasement for the garments hung therein, 40 an abutment at the inner margin of the guard, and a removable receptacle forming an internal cover for the main section and of a depth substantially equal to the width of the guard and adapted to be positioned in 45 the main section in said guard and against said abutment.

50 2. A wardrobe type suit case, comprising a main section, a closure for the section, means hingedly connecting the section and closure whereby the closure is movable upon an axis substantially at right angles with the main section bottom, the bottom of the closure being on a higher plane than the bottom of the section, an extension on the bottom of the 55 section and forming therewith a one-piece

bottom for the case, said extension filling the space beneath the closure bottom, wardrobe means within the section whereby garments hung therefrom may have their lower portions extended into a well formed by the bottom portion of the section and the interior of said extension, and an article receiving container of a width substantially equal to the width of said section of a height to substantially fill the open face of the section and adapted to be secured therein with its lower portion extended into said extension. 70

3. A baggage carrier, comprising a main section, a closure, means hingedly connecting the section and closure, the bottom of the closure being on a higher plane than the bottom of the section, an extension on the bottom of the section and forming therewith a one-piece bottom for the carrier, said extension filling the space beneath the carrier closure, wardrobe means within the section, an article carrying container removably fitted in the section outwardly of and over the wardrobe means to cover the same, said container extending beyond the marginal edges of the section and into the closure when the carrier is closed, and cooperating means carried by the container and section to removably secure the container within the carrier. 80

4. A baggage carrier, comprising a main section, a closure, means hingedly connecting the closure with the section, the bottom of the closure being on a higher plane than the bottom of the section, an extension on the bottom of the section and forming therewith a one-piece bottom for the carrier, said extension filling the space beneath the closure, wardrobe supporting means in the section, a container mounted within the section, its outer portion projecting beyond the section and into the closure when closed, means removably securing the container in the section, and said wardrobe supporting means extending over the container and beyond the section and into the closure whereby the carrier may be used entirely for garments when the container is removed. 100

5. In a wardrobe type suit case having a main section provided with means from which wardrobe is adapted to be hung, a closure for the open front of the main section with its bottom terminating short of the bottom of the main section, an extension on the bottom of the main section and filling the space beneath the closure whereby the carrier has a uniform external appearance when the closure is closed on the main section, a detachable article containing member normally disposed over substantially the entire open face of the body section to provide an internal cover for wardrobe hung therein, and means supporting said detachable article container in the main section over the 115 120 125 130

open face thereof with the front vertical face in substantially the same plane as the outer end of said extension member whereby the same nests in the closure when closed.

5 In testimony whereof I affix my signature.

GEORGE HENRY WHEARY.
